UNITED STATES PATENT OFFICE

2,669,104

KNITTING MACHINE

Alexander Belford, Laconia, N. H., assignor to
 Scott & Williams, Incorporated, Laconia, N. H.,
 a corporation of Massachusetts

Application June 19, 1951, Serial No. 232,315

13 Claims. (Cl. 66—135)

1

This invention relates to knitting machines and has particular reference to the mechanism involved in the formation of wrap patterns.

Satisfactory wrapping requires good plating of stitches by the wrap yarns. It is known that proper plating may be best secured by maintaining proper control of the incorporated wrap yarn during the formation of stitches by means of a wrap horn about which the yarn used in wrapping extends from a previous stitch in which it was incorporated to the needle or needles which are being moved to draw stitches. For this purpose, such a horn in a circular knitting machine extends through an arc inside the needle circle terminating generally at a point in the vicinity of the bottom of the stitch cam which draws the needles downwardly for the formation of stitches. Desirably, such a wrap horn tapers to substantially a point which desirably is located very close to the finished fabric level.

The form and arrangement of the wrap horn just mentioned are satisfactory when there is no interference by it with other elements of the knitting mechanism. In the case of machines which through the provision of dial needles cooperating with cylinder needles provide integral rib tops for stockings, the dial needles are located inside the needle circle and are arranged to project across the needle circle during operation. Under these conditions, it will be evident that it is impossible to provide a wrap horn in the most desirable position of close approach to the fabric without interference with the dial needle operation. Furthermore, mere movement by raising or lowering of the horn will not suffice inasmuch as the horn projects through a considerable circumferential arc and past the locations of abutments for the wrap yarns which serve to effect a sweep of the wrap yarns for the purpose of wrapping selected needles.

One object of the present invention is the provision of a movable wrap horn which, when the dial needles are active and at other desirable times, such as during heel and toe formation, may be raised sufficiently to avoid interference with these operations, while at the same time provision is made for locating the free end of the wrap horn closely adjacent to the fabric level for the satisfactory formation of properly plated wrap stitches. In accordance with the invention the wrap horn is pivoted. The axis for this pivoting is at such a location that a real axis cannot be provided by a shaft or the equivalent. Accordingly, a mounting for the wrap horn is provided which affords a virtual axis for its pivoting movements. This axis is such that the

2

trailing end of the wrap horn may be moved substantially vertically from a position closely adjacent to the fabric to a sufficiently raised position to clear dial needles which are outwardly projected. At the same time, the axis is so located that in the vicinity of the wrap yarn abutments those slight motions which do occur, occur in such fashion as to avoid engagement of the wrap horn with the abutments thus avoiding any necessity for providing movable abutments. It is a further object of the present invention to provide for fine adjustment of the wrap horn in a circumferential direction to bring its most important trailing end in precisely proper relationship to the stitch cam for the cylinder needles to insure proper plating.

These and other objects of the invention particularly relating to details of construction and operation will become apparent from the following description read in conjunction with the accompanying drawings, in which:

Figure 1 is a fragmentary axial section showing in particular the meeting regions of the cylinder and dial of an automatic rib top machine and the mounting arrangement for a wrap horn arranged in accordance with the invention;

Figure 2 is a horizontal section showing the mounting arrangement for the wrap horn; and

Figure 3 is a developed view looking outwardly showing the mounting of the wrap horn with reference to other elements of the machine including certain of the cams which cooperate in the formation of wrapped stitches.

The needle cylinder of a rotary cylinder circular knitting machine is shown at 2 which carries in axially extending slots needles 4. The machine particularly illustrated may be of the type shown in greater detail in the patent to Grothey 2,411,422, dated November 19, 1946. As shown in this patent, there are located under the needles 4 jacks which are adapted to be acted upon by suitable cams for the selection of needles upwardly for wrapping. Cooperating with the cylinder needles are the usual sinkers 6 over the ledges of which stitches are drawn. The usual latch ring shown at 10 carries the latch guard indicated at 8 located immediately outside the needle circle.

A dial 14 which is mounted in conventional fashion for rotation with the needle cylinder carries in slots thereof the radially extending elements 13 and 20 providing dial needles which elements have butts arranged to be acted upon in conventional fashion by cams carried by the dial cap 16.

As illustrated and described in detail in said

Grothey patent, wrap fingers 22 are suitably mounted for rotation generally with the needle cylinder but for additional shogging movements with respect thereto, these wrap fingers 22 being provided with butts 26 arranged to be acted upon by cams (not shown) to secure selective activation of these fingers.

The parts so far described are conventional and are illustrated more fully in said Grothey patent to which reference may be made for details.

Mounted on the latch ring 10 is a bracket 28 carrying a pair of bolts 30 and 32 which project through respective slots 34 and 36 in a carrier member 37 which is normally held in upper position with respect to the bracket 28 by a spring 38 reacting between a pin 40 carried by the carrier and a pin 42 carried by the bracket. The carrier 37 has a slot 44 in its upper end within which there engages the pin 46 carried by a member 45 which is pivoted on a push rod 48, being restrained from lengthwise movement with respect to the push rod by a collar 47. A bracket 50 guides the push rod for vertical movement. This push rod is adapted to be acted upon by cams on the main cam drum of the machine and is the push rod which controls the active or inactive positions of the cams acting on the butts 26 of the wrap fingers 22. This push rod is illustrated more fully in said Grothey patent. When the rod 48 is in its lowermost position, the wrap finger actuating cams are inactive and, under such conditions, the support 37 is moved downwardly against the tension of spring 38 serving, as will appear hereafter, to raise to inactive position the wrap horn. On the other hand, when the rod 48 is in upper position, the support 37 is also raised rendering the wrap horn active, the position of the wrap horn corresponding to active position of the cams which act on the wrap yarn fingers.

The support 37 has a portion 52 with downwardly extending flanges engaging an arcuate track 54 which is provided on the shank 56 of the wrap horn. At the ends of this track there are upstanding lugs 58 and 60 through which are threaded respectively the screws 62 and 64 which may be brought to bear on the ends of the member 52. The member is provided with a slot 66 through which passes a clamping screw 68 which is threaded into the shank 56 of the wrap horn.

As will be evident from the several figures, the shank 56 has an inwardly and downwardly directed extension 70 from which there extends the arcuate wrap horn 72 terminating in a tapered portion leading to the pointed end 74. The shape of this wrap horn will be evident from consideration of the development shown in Figure 3.

At 76 and 78 there are shown the wrap yarn abutments of the type illustrated more particularly in said Grothey patent. These abutments extend over the needle circle and, as will be evident, are directly above the wrap horn. It is necessary that the tilting of the wrap horn should not cause it to engage these abutments. The most important portion of the wrap horn from the standpoint of securing clean-cut wrapping of the stitches is the end 74. The mounting arrangement which has been described involving the sliding of the slots 34 and 36 over the bolts 30 and 32 provides tilting about an axis which is approximately in the position illustrated at D in Figure 1. This axis is close from the standpoint of axial projection to the wrap yarn abutments 76 and 78 and, as a result, the tilting of the wrap horn does

not result in its being substantially lifted in the vicinity of the abutments. Rather, it has only a relatively slight movement primarily in a horizontal direction. Accordingly, there is no interference with these abutments.

Furthermore, as will become evident from Figure 3, the major portion of the wrap horn past the vicinity of these abutments may be at a substantial height above the sinker ledges which define the vertical position of the formed fabric. Accordingly, there is a clear space, as will appear in Figure 1, for the projection of the dial needle elements. Adjacent to the point end 74, however, the wrap horn has a quite substantial vertical movement when it is rocked and the end 74 will move to a position such as indicated at 74' above the level of the dial needles to provide a sufficient clearance for the projection of the dial needle elements when these are operating.

It is not necessary in the present instances to describe in detail the camming of the selecting jacks and needles, but to make clear the relative positions of the parts, there are indicated in Figure 3 various cams. Cams 80 and 82 act upon the jacks while cams 84, 86, 88 and 90 are the cams which control the butts of needles 4 for upward and then downward movements for wrapping at the two wrap points. Cam 92 is the stitch cam which has a lower point 94 substantially directly above which there is located the pointed end 74 of the wrap horn. The paths indicated at A, A' and A'' and at B, B' and B'' are, respectively, the paths followed by the hooks of selected needles and the ends of their open latches. At C there is indicated the level of the sinker ledges which is approximately the level of the fabric as the fabric leaves the needles. It will be observed that the end 74 of the wrap horn when it is in active position is substantially at this level. The result is effective control of the wrap yarns during stitch formation to secure good plating. The main yarn or yarns are fed to the needles at approximately the position indicated at E.

As the result of the foregoing it will be noted that the wrap yarns are held under control by the wrap horn until the stitches which are to be plated are completely drawn while, nevertheless, during rib knitting the wrap horn may be moved to an inactive position clearing throughout its length a space for the projection of the dial needle elements. As indicated above, it is also desirable that the wrap horn should be raised during heel and toe knitting and this may be accomplished through the control of the push rod 48. The pin 46 by reason of its pivotal movement on the push rod 48 may be moved outwardly to an inactive position when it is necessary to raise the latch ring in conventional fashion.

The adjustment of the wrap horn circumferentially is of importance to secure best wrap plating conditions and this adjustment may be made for the knitting of yarns of various weights. The adjustment is simply effected by feeding the clamping screw 68 and adjusting the wrap horn circumferentially by means of the screws 62 and 64 whereupon the wrap horn may be locked in finally adjusted position by the tightening of screw 68.

What is claimed is:

1. A knitting machine comprising a rotary cylinder, a rotary dial, needles carried by said cylinder and said dial for the formation of a rib fabric, a latch ring, a wrap yarn carrier for the presentation of a wrap yarn to cylinder needles, a wrap horn extending in an arc adjacent to the

cylinder needles, and means mounting said horn for tilting movements of a portion thereof relatively to the latch ring in a generally axial direction.

2. A knitting machine comprising a rotary cylinder, a rotary dial, needles carried by said cylinder and said dial for the formation of rib fabric, a latch ring, a stitch cam for moving cylinder needles for the drawing of stitches, a wrap yarn carrier for the presentation of a wrap yarn to cylinder needles, a wrap horn extending in an arc adjacent to the cylinder needles and having its trailing end terminating substantially at the circumferential position of the lower end of said stitch cam, and means mounting said horn for tilting movements of a portion thereof relatively to the latch ring in a generally axial direction.

3. A knitting machine comprising a rotary cylinder, a rotary dial, needles carried by said cylinder and said dial for the formation of rib fabric, a wrap yarn carrier for the presentation of a wrap yarn to cylinder needles, an abutment for engaging and retarding the wrap yarn relatively to the needles, a wrap horn extending in an arc adjacent to the cylinder needles, and means mounting said horn for movements of a portion thereof in a generally axial direction without substantial axial movement of the wrap horn in the vicinity of said abutment.

4. A knitting machine comprising a rotary cylinder, a rotary dial, needles carried by said cylinder and said dial for the formation of rib fabric, a stitch cam for moving cylinder needles for the drawing of stitches, a wrap yarn carrier for the presentation of a wrap yarn to cylinder needles, an abutment for engaging and retarding the wrap yarn relatively to the needles, a wrap horn extending in an arc adjacent to the cylinder needles and having its trailing end terminating substantially at the circumferential position of the lower end of said stitch cam, and means mounting said horn for movements of a portion thereof in a generally axial direction without substantial axial movement of the wrap horn in the vicinity of said abutment.

5. A knitting machine comprising a rotary cylinder, a rotary dial, needles carried by said cylinder and said dial for the formation of rib fabric, a wrap yarn carrier for the presentation of a wrap yarn to cylinder needles, a wrap horn extending in an arc adjacent to the cylinder needles, and means mounting said horn for tilting movements of a portion thereof in a generally axial direction, said mounting means comprising a pair of pin and slot connections between said wrap horn and a fixed portion of the machine.

6. A knitting machine comprising a rotary cylinder, a rotary dial, needles carried by said cylinder and said dial for the formation of rib fabric, a stitch cam for moving cylinder needles for the drawing of stitches, a wrap yarn carrier for the presentation of a wrap yarn to cylinder needles, a wrap horn extending in an arc adjacent to the cylinder needles and having its trailing end terminating substantially at the circumferential position of the lower end of said stitch cam, and means mounting said horn for tilting movements of a portion thereof in a generally axial direction, said mounting means comprising a pair of pin and slot connections between said wrap horn and a fixed portion of the machine.

7. A knitting machine comprising a rotary cylinder, a rotary dial, needles carried by said cylinder and said dial for the formation of rib fabric, a wrap yarn carrier for the presentation of a wrap yarn to cylinder needles, an abutment for

engaging and retarding the wrap yarn relatively to the needles, a wrap horn extending in an arc adjacent to the cylinder needles, and means mounting said horn for movements of a portion thereof in a generally axial direction without substantial axial movement of the wrap horn in the vicinity of said abutment, said mounting means comprising a pair of pin and slot connections between said wrap horn and a fixed portion of the machine.

8. A knitting machine comprising a rotary cylinder, a rotary dial, needles carried by said cylinder and said dial for the formation of rib fabric, a stitch cam for moving cylinder needles for the drawing of stitches, a wrap yarn carrier for the presentation of a wrap yarn to cylinder needles, an abutment for engaging and retarding the wrap yarn relatively to the needles, a wrap horn extending in an arc adjacent to the cylinder needles and having its trailing end terminating substantially at the circumferential position of the lower end of said stitch cam, and means mounting said horn for movements of a portion thereof in a generally axial direction without substantial axial movement of the wrap horn in the vicinity of said abutment, said mounting means comprising a pair of pin and slot connections between said wrap horn and a fixed portion of the machine.

9. A knitting machine comprising a rotary cylinder, a rotary dial, needles carried by said cylinder and said dial for the formation of rib fabric, a wrap yarn carrier for the presentation of a wrap yarn to cylinder needles, a wrap horn extending in an arc adjacent to the cylinder needles, and means mounting said horn for movements of the trailing end thereof in a generally axial direction between an active position below and an inactive position above the said dial needles.

10. A knitting machine comprising a rotary cylinder, a rotary dial, needles carried by said cylinder and said dial for the formation of a rib fabric, a latch ring, a wrap yarn carrier for the presentation of a wrap yarn to cylinder needles, a wrap horn extending in an arc adjacent to the cylinder needles, and means mounting said horn for circumferential adjustment about the axis of the cylinder and for tilting movements of a portion thereof relatively to the latch ring in a generally axial direction.

11. A knitting machine comprising a rotary cylinder, a rotary dial, needles carried by said cylinder and said dial for the formation of rib fabric, a wrap yarn carrier for the presentation of a wrap yarn to cylinder needles, an abutment for engaging and retarding the wrap yarn relatively to the needles, a wrap horn extending in an arc adjacent to the cylinder needles, and means mounting said horn for circumferential adjustment about the axis of the cylinder and for movements of a portion thereof in a generally axial direction without substantial axial movement of the wrap horn in the vicinity of said abutment.

12. A knitting machine comprising a rotary cylinder, a rotary dial, needles carried by said cylinder and said dial for the formation of rib fabric, a wrap yarn carrier for the presentation of a wrap yarn to cylinder needles, a wrap horn extending in an arc adjacent to the cylinder needles, and means mounting said horn for circumferential adjustment about the axis of the cylinder and for movements of the trailing end thereof in a generally axial direction between an active position below and an inactive position above the said dial needles.

13. A knitting machine comprising a rotary cylinder, a rotary dial, needles carried by said

cylinder and said dial for the formation of rib fabric, a stitch cam for moving cylinder needles for the drawing of stitches, a wrap yarn carrier for the presentation of a wrap yarn to cylinder needles, a wrap horn extending in an arc adjacent to the cylinder needles and having its trailing end terminating substantially at the circumferential position of the lower end of said stitch cam, and means mounting said horn for movements of the trailing end thereof in a generally 10 axial direction between an active position below and an inactive position above the said dial needles.
